UNITED STATES PATENT OFFICE.

EDWARD JORDAN, OF NEWTON, NEW SOUTH WALES, AUSTRALIA.

LAUNDRY DRIPBOARD.

1,138,661.

Specification of Letters Patent.

Patented May 11, 1915.

Application filed May 4, 1914. Serial No. 836,145.

To all whom it may concern:

Be it known that I, EDWARD JORDAN, gentleman, a subject of the King of Great Britain and Ireland, residing at 126 Station 5 street, Newton, in the State of New South Wales and Commonwealth of Australia, have invented a new and useful Improved Laundry Dripboard, of which the following is a specification.

10 This invention relates to improvements in drip-boards for laundry work, and the object of the invention is to provide a cheap and simple drip-board which is adapted to be used for a two-fold purpose.

15 The first and principal purpose of the invention is to bridge the distance between the washing boiler or copper and the washtub so that the boiled clothes can be removed from the boiler on to and over this drip-20 board into the washtub so that the dripping suds water will pass back into the boiler thereby avoiding excessive waste, and at the same time minimizing the quantity of suds water passing into the wash tub containing 25 the rinsing water, and furthermore the drip-board is so constructed that no suds water can fall into the space or portion that generally exists between the said washing boiler and the washtub, providing the drip-board 30 is made long enough to bridge over the space.

The second purpose of the invention is that it can conveniently be used as a transporting tray for the clothes after they have 35 been rinsed and ready for drying.

A dripboard constructed according to this invention consists of a longitudinally arched bottom supported by longitudinal cheeks one end of which rests upon the wash-40 ing boiler, the other upon the washtub. The cheeks projecting upwardly above the arched bottom so as to form side flanges, the upper edges of which are preferably of the same contour as the arched bottom.

45 Beneath the arched bottom are lateral bearers, one of which is provided with a depending lug adapted to take against the inner periphery of the wash boiler edge, and the other which is of sufficient length to 50 bridge the largest type of household washing tub, has adjustable lugs for securing the drip-board in a firm position on any size of tub while the clothes are being lifted from the boiler on to the board and thence 55 into the tub. The receiving end of the

arched bottom situated over the boiler is segmental in shape.

Above the arched bottom are a series of spaced lateral laths that have a clearance space beneath so that when the clothes are 60 lifted out of the boiler on to the laths, the dripping suds water may pass between the laths and the arched bottom underneath back into the boiler.

The laths extend from the receiving end 65 of the board to the highest point of the arched bottom.

When rinsing the clothes the segmental or receiving end of the dripboard is placed over the rinsing tub, so that when the rinsed 70 clothes are placed upon the laths the dripping suds water may pass back into the said tub. The rinsed clothes may then be transported to where desired for drying by using the dripboard as a tray. But in order that 75 the invention may be more clearly understood reference will now be made to the drawings in which—

Figure 1 is a perspective view of the drip-80 board. Fig. 2 a longitudinal sectional elevation. Fig. 3 a cross sectional elevation.

The longitudinally arched bottom 5 has one inclination longer than the other and is secured underneath to the bearers 6 that are rigidly fixed to the side cheeks or supports 85 7 which also form flanges above the bottom 5. Above the longer inclination are lateral laths 8 secured to the upper surface of the bearers 6.

The end 9 of the longer inclination of the 90 arched bottom 5 is segmental in shape, and below the arched bottom are lateral strengthening pieces 10 and 11 the former having a pivoted lug 12 adapted to engage with the boiler 13. Also affixed to the cheeks and 95 underneath the bottom is a bearer 14 having stop pieces 15 adapted to engage with the washtub 16 thereby securing the dripboard in position.

In use when removing boiled clothes from 100 the boiler 13 the dripboard is so situated that the segmental end 9 of the arched bottom 5 is placed over the boiler, and the lug 12 turned down while also the lugs 15 are 105 adjusted at the tub end 16 thereby securing the dripboard firmly in position as the clothes are lifted up out of the boiler upon the laths 8, the dripping suds water passing down between the laths to the bottom 5 back into the boiler 13.

When rinsing the clothes the dripboard is reversed so that the segmental end 9 is placed over the rinsing tub, the clothes are then placed on the laths thus allowing the 5 dripping water to pass back in the tub.

The rinsed clothes may then be transported to where desired by using the drip-board as a tray.

I claim:—

10 An improved laundry dripboard comprising a longitudinally-arched bottom having one inclination longer than the other, the free end of the longer inclination being of a segmental shape, bearers, to the underside

of which is secured the arched bottom, sides 15 to which the bearers are secured, transverse pieces secured to the top of the bearers above the longer inclination, said sides projecting above the bottom and transverse pieces, lateral strengthening pieces below the arched 20 bottom, a pivoted lug for one of said pieces adapted to engage the boiler, and a bearer affixed to said sides below the bottom, having stop pieces secured to it.

EDWARD JORDAN.
